UNITED STATES PATENT OFFICE.

ARTHUR KORN, OF CHARLOTTENBURG, NEAR BERLIN, GERMANY.

PHOTOTELEGRAPH.

Application filed May 5, 1923, Serial No. 636,871, and in Germany November 12, 1921.

This invention refers to improvements in automatic phototelegraphs, and in particular to that kind of apparatus of this kind which are provided with photoelectric cells in the transmitter, and it is particularly intended among other objects and advantages to increase the adaptability of the so-called compensation method, and to generally improve and perfect the arrangement, operation and construction of apparatus of this kind.

In my U. S. Patent 888,098 I have described a method for considerably diminishing the errors due to inertia, and occurring in the transmitters of phototelegraphic devices with selenium cells by using a combination of a feeler cell with a compensation cell.

Besides the selenium cells referred to there are, however, still other photoelectric cells the variations of resistance of which upon exposure to light are considerably inferior to the changes of resistance of selenium cells, and of these I may mention the photoelectric cells according to Elster, Geitel and others by way of example. In accordance with my invention means are provided for an improved arrangement of compensating means making it possible, when applied not only to selenium cells but also to any of the other weakly sensible photoelectric cells to produce satisfactory and even better results for larger distances than with the compensation method heretofore known. In the same manner as selenium cells every other photoelectric cells, that is to say, every compound the electric resistance of which is changed upon exposure to light, as well as the corresponding pieces of apparatus for registering these changes and variations, exhibit a certain inertia, so that for instance the increment of current transmitted through a cell from a constant battery, and registered by the device, and provided the irradiation at the time of commencement $t=0$ shows the increment ΔI is represented approximately by the formula:—

$$\Delta i = \alpha \Delta I e^{-\frac{\beta}{\gamma t}}$$

in which formula α , β , γ are constants of the cell peculiar to the electromotive force employed and in accordance with the properties of the registering devices; α is the

"sensitiveness" the following ratio holding, viz,

$$t = \infty : \Delta i = \alpha \Delta I$$

55

β is the constant of inertia proper. The more the value of t is increased the slower the value of Δi comes near asymptotically to the value $\alpha \Delta I : \gamma$ in a great number of selenium cells is equal to $=3/2$. The proportionality of $\Delta i_{t=\infty}$ with ΔI holds true only approximately, and the least in the vicinity of the zero irradiation. In the practice of my invention in view of these facts in the vicinity of the zero irradiation a constant preliminary irradiation is imparted to the photoelectric cells in phototelegraphic transmission, whereby the error referred to is obviated.

In pursuance of the compensation method otherwise known two photoelectric cells are exposed simultaneously to the variations of irradiation ΔI , and for the bridge current passing through the registering device, a galvanometer for instance, and furnished by a Wheatstone bridge formed by the cells and suitable resistances a value of current is obtained corresponding to the difference of the two changes of resistance of the two cells. Thus the formula becomes:—

$$\Delta i = (\alpha_1 e^{-\frac{\beta_1}{\gamma t}} - \alpha_2 e^{-\frac{\beta_2}{\gamma t}}) \Delta I$$

in which formula α_1, β_1 are the two respective constants of one of the cells, α_2, β_2 are the two constants of the other cell. The constant γ for general practice may be assumed to be the same with suitable selection of both cells.

It is of essential importance in this connection with regard to the efficiency of operation of the compensation that the curve of the differences (Δi ordinate, and t abscissa) becomes almost parallel to the abscissa as quickly as possible, so that:—

$$\frac{d \Delta i}{d t} = 0$$

resulting as the condition for compensation in the values:—

$$\alpha_1 \beta_1 - \alpha_2 \beta_2 = 0$$

In view of the fact that $\alpha_1 - \alpha_2$ should be > 0 it follows that the sensitiveness of

the feeler cell should be greater and its inertia should be less than the corresponding values of the compensation cell.

The compensation method may be improved, provided the changes of irradiation are received by the compensation cell later than by the feeler cell. This object may be accomplished by a suitable selection of the arrangement of the apparatus, or causing a small section of the transparent field of irradiation to be exposed in such a manner that the retardation is produced by the movement of the picture carriers, so that the field to be irradiated upon its passage through the cone of light is successively producing an impression of light upon the photoelectric cells.

In order to further perfect the action of the compensation reinforcing members or valves are inserted intermediate the feeler cell and the registering means, so that increased currents are either fed to the galvanometer of the compensation cell, or to the galvanometer at the receiving station or to both of them at the same time in accordance with the general requirements of transmission.

The invention will be more fully explained with reference to the accompanying drawings, showing by way of example and in a conventional way an example of embodying the principles of my invention. In the drawings:-

Figure 1 illustrates diagrammatically the relative arrangement of the several pieces of apparatus and their electric connection. Figure 2 is an elevation of the transmitter, the source of light being removed in conformity with line 2-2 in Figure 3. In Figure 3 I have shown a sectional view on the line 3-3 of Figure 2, and Figure 4 is a section through the compensation cell on the line 4-4 of Figure 5. Figure 5 is a section on the line 5-5 of Figure 4. In Figures 6 and 7 different positions of the so-called chord galvanometer are shown in accordance with Figures 4 and 5. Figure 8 illustrates a sectional view of the transmitter in accordance with Figure 2 but somewhat modified, on the line 8-8 Figure 9, and Figure 9 is a section on the line 9-9 of Figure 8. Figure 10 is a section on the line 10-10 of Figure 8. Figure 11 shows the picture carrier in elevation with two irradiation surfaces. Figures 12 and 13 are graphical representations of the irradiation curves. Figure 14 illustrates diagrammatically the arrangement of producing the retardation by the movement of the picture carrier.

In the transmission of pictures and the like by phototelegraphic means the film with the picture is placed upon a transparent glass cylinder 11 which is mounted upon a

plate 12 supported from a spindle or shaft 13 provided with fine screw threads and adapted to be displaced in a stationary internally screw threaded nut 14. The plate 12 is guided by means of rollers 15 upon the ribs 16 of the casing 17 which in its turn by means of the hollow trunnion 18 is guided in the bearing 19. This bearing 19 is supported by means of the brackets 20 on a casing 21 in which the glass cylinder 11 is adapted to rotate. On the hollow trunnion 18 a worm wheel 22 is mounted which may be driven by means of the worm 23 of a motor engine 24. Upon the rotation of the worm wheel 22 the casing 17 is rotated and carries the glass cylinder 11 along with it in its movement by means of the rollers 15 and the plate 12. By this means the shaft 13 is rotated and screw threaded ascends in the nut 14, so that the glass cylinder 11 is also moved upwards in a helical path.

Upon the bottom of the casing 21 the feeler cell 25 is mounted which may either comprise a selenium cell or any other suitable cell, thus for instance a cell according to Elster and Geitel. Above the feeler cell 25 a prism 26 adapted for total reflection is mounted supported upon a pillar or the like 27. Upon the casing 21 a tubular projection 28 with a lens 29 is arranged in front of which a strong source of light is mounted comprising a shell 30, a lamp 31 and an adjustable condenser lens 32. The shell 30 is provided with a threaded stud 33 guided in a support 34, and capable of vertical adjustment by means of the nut 35. The lamp 31 is adjusted in such a manner by means of the nut 35 that it projects its cone of light upon the lens 29 from which the pencil of rays is projected upon a point on the picture carrier of the glass cylinder 11. The light permeates the glass cylinder more or less in accordance with the opaqueness of the picture carrier, and strikes the prism 26 from which it is projected to the feeler cell 25.

In accordance with the illustration in Figures 4 to 7 the compensation cell 36 is mounted in a casing 37 which is preferably closed on top by glass rods 38. Above the casing 37 a prism 40 is provided on a support 39 upon which the light of the source of light is projected comprising a shell or casing 41 with a lamp 42 mounted therein, and closed in front by an adjustable condenser lens 43. The casing 41 is supported on the threaded stud 44 which by means of the nut 46 may be exactly adjusted in the vertical direction. Between the lamp and the prism 40 a chord-galvanometer is mounted. This galvanometer comprises a base 47 upon which two coils 48 are mounted surrounding a magnet core provided with two pole shoes 49. Apertures 50 are provided in

the pole shoes through which the light of the lamp is adapted to pass. The pole shoe confronting the prism 40 is provided with a tube 51 upon which a lens 53 may be disposed by means of the collars 52, said lens 53 throwing the light of the lamp upon the prism which in its turn projects the rays of light upon the compensation cell 36. Between the pole shoes 49 a frame 54 is arranged at one end of which a rigidly secured stud 55 with a roller 56 is mounted and adapted for connection with the conducting wire by means of the clamping screw 57. At the other end of said frame 54 a stud 59 with roller 60 is adjustably secured by means of the nut 58, and to which the other conducting wire may be secured by means of the screw 61. The studs 55 and 59 are carefully insulated in the frame 54 by means of the insulation 62, and over the rollers 56 and 60 an endless wire 63 is placed between the two sections of which a small foil 64 is mounted in such a manner that it is situated exactly within the pencil of rays emanating from the source of light. This wire is in electric connection with the circuit of the feeling cell, so that the movement of the foil or respectively of the wire 63 is governed by the change of current condition in the said feeling-circuit and the foil may thus be employed as a means to indicate the change of current condition, and by controlling and regulating the passage of light from the source of light to the compensating cell owing to its movement this cell 36 is varyingly optically influenced, and the foil or wire 63 of the galvanometer on the sending and transmitting station acts as a kind of telegraph, the changing condition of which is transmitted to a similar or equivalent member 81 at the receiving station.

In accordance with Figure 7 the position of rest of the foil 64 and of the wire 63 are relatively arranged in such a manner that to a small extent the light is already capable to penetrate to the compensation cell 36. This position is the extreme position of interception so that a permanent weak irradiation of the cell will be secured. This is the preliminary irradiation which is necessary for the successful operation of the compensation cell. A permanent preliminary irradiation of feeler cell is accomplished in view of the fact that in the original films to be employed a certain transparency exists also in the darkest sections of the picture; if desired, a preliminary irradiation of the feeler cell may be produced by a separate source of light. In accordance with the degree of transparency of the picture carrier the wire 63 is capable of swinging more or less in conformity with the current impulses admitted thereto, the said wire being adapted for instance to oscillate around half of Figure 6 or around the entire Figure 4, so as to permit the passage of the rays of light of the lamp to the cell 36 more or less.

The device hereintofore described will operate as follows in accordance with Figure 1:

From a source of current, a battery 65 for instance the current passes through the conductor 66 to the compensation cell 36, and thence through the conductor 67 to the feeler cell 25 which is connected by the conductor 68 to the other terminal of the battery 65. Between the two conductors 66 and 68 a connecting conductor 69 is shunted with a resistance 70 along which a contact piece 71 is adapted to slide which is itself electrically connected by the conductor 72 with the reinforcer-tube arrangement 73 from which the conductor 74, 75 leads to the conductor 67 intermediate the two photoelectric cells 25 and 36. The conductor section from the contact piece 71 to the conductor 67 constitutes the Wheatstone-bridge. A resistance 76 is shunted around the compensation cell 36 and is connected at one end by means of the conductor 77 to the conductor 67, and over the conductor 77, while a contact piece 78 movable along the resistance 76 is connected to the conductor 66 over the conductor 79.

From the reinforcer lamps 73 the conductor 80 passes to the receiving apparatus, and to one terminal of the chord galvanometer mounted at 81 of the same construction as the galvanometer described with reference to Figures 4 to 7, and the other terminal of which is connected to the return conductor 82 which leads back to the reinforcer lamps 73. The receiving means comprise a light-sensitive film wound upon a drum 83, and upon which the light of a lamp 84 is projected by the lenses 85, 86. The receiving means are otherwise of the same construction as the transmitting and sending apparatus shown in Figures 2 and 3. Intermediate the lamp 84 and the lens 86 the foil 87 of the galvanometer is situated the oscillations of which expose areas of varying size of the admission opening for the rays of light to the light sensitive film upon the drum 83.

At the transmitting station a conductor 88 is branched off from the conductor 82 and leads to the frame of the galvanometer in accordance with the illustration Figures 4 to 7. The other end of the chord galvanometer is connected by a conductor 89 to the resistance 90 along which a sliding contact piece 91 is adapted to move which is connected by means of the conductor 92 to the conductor 80. The chord galvanometer by means of its foil 64, regulates and controls the admission of light from the lamp 42 to the compensation cell 36. In view of the fact that the galvanometer for the compensation cell

receives the currents which are reinforced by the arrangement of reinforcing lamps the oscillations of the galvanometer are considerably larger, so that the compensating action of the compensation cell becomes highly increased and improved.

It is of essential importance for the compensation that the curve of difference is quickly rising to a constant magnitude. In 10 Figure 12 I have shown a graph of the formation of the curve. Let Δi be the ordinate, and t the abscissa. The two curves Δi_1 and Δi_2 represent the variations of the values of the resistance of the two cells 25 and 36, and 15 the curve of differences Δi extends between those two curves in such a manner that it approaches asymptotically the value of ΔJ .

This action may be considerably improved by causing the irradiation of the compensation cell to be accomplished somewhat in ar- 20 rear, that is to say, being for instance retarded for the value t , but then the more rapidly. In this case the several curves will assume the graphical configuration in ac- 25 cordance with Figure 13, the curve of differences showing a protruding hunch β at its commencement, and thereafter merging the more rapidly into the constant limit.

In the arrangement as shown in Figures 1 30 to 7 the retardation is produced by the inertia of the system of irradiation of compensation cells, inasmuch as the transmission to the corresponding chord galvanometer and the corresponding pieces of apparatus requires a certain period of time.

The retardation may, however, also be effected in other ways; thus, for instance by causing the irradiation of the compensating cell 36 to be produced by the same source of 40 light, as employed for the feeler cell 25, and preferably by permeating through the picture carrier. Inasmuch as these two cells should be arranged side by side of each other the same section of the picture carrier upon 45 its movement through the pencil of rays of the irradiating lamp will project the amount of irradiation proportionally corresponding to the feeler cell 25 upon the compensation cell only with some retardation, whereby the 50 desired retarding action is produced.

Means for accomplishing this object are shown by way of example in Figures 8, 9, 10, 11 and 14 of the drawing. In this case the mechanical portion of the transmitter is constructed so as to exactly correspond to Figures 2 and 3, with the difference however that at the rear of the lens 29 a shutter 94 is mounted provided with a slot 95 elongated in the direction of rotation of the drum 11. 60 The light of the lamp 31 is so arranged that upon the picture carrier a section corresponding to the slot 95 receives the irradiation. The rays of light penetrating through the slot 95 are not thrown in a body upon a 65 cell, but they are distributed over the two

cells 25 and 36, so that the irradiated portion of the picture carrier, so to speak, is divided into two sections 96 and 97 (Figure 11). In view of the fact that the transparency of the picture carrier varies with the

photographic picture, and inasmuch as the section 96 replaces the section 97 only upon continuing the rotation in the direction of the arrow 98, this action results in a retardation in the irradiation of the compensation cell 36 which is governed exactly by the circumferential velocity of the picture carrier.

11. In this case the electric connections should be changed somewhat, as shown in Figure 14 of the drawing. As shown in this

figure the current passes from the battery 99 and over the conductor 100 to the compensation cell 36, thence by way of the conductor 101 to the feeler cell 25, and back through conductor 102 to the other terminal of the 85 battery 99. Intermediate the two conductors 100 and 102 the resistance 103 is shunted between which and the conductor 101 the Wheatstone-bridge is formed which consists of the contact piece 104 movable and adjustable along the resistance 103, the conductor 105 which leads to the combination of reinforcing tubes 106, and the conductor 107 leading to the conductor 101. In parallel to the compensation cell 36 the resistance 108 is arranged which is connected by the conductor 109 to the conductor 101 and upon which a sliding contact 110 is adapted to move which is itself connected to the conductor 100 over the conductor 111. From the reinforcing tubes 106 the two conductors 112 and 113 lead to the registering device 114 of the receiving station.

As hereinbefore set forth, it has been assumed that the current emanating from the reinforcing tubes or equivalent means are conducted directly to the receiving station by conducting wires. It is obvious, however, that the currents may also be transmitted by wireless methods, without requiring any change in the principles and the system in accordance with my invention. Furthermore than that, the indicated and registered currents may be employed for the purpose of the production of perforated registration strips or of typed telegrams from which the message may then be transmitted in the usual manner, by wireless, by cable or by telegraphic or telephonic conducting lines to the receiving station, so as to serve as a means for the assembling and reproduction of the picture at the receiving station.

I also wish it to be understood that my invention is susceptible of various embodiments other than those shown and hereinbefore described by way of example and for convenience of illustration, the drawings being more or less conventional, and not being intended for limiting the invention to any particular form and arrangement of

parts, but various changes and modifications may occur to the expert to better adapt the invention to varying conditions of application, and to the convenience of the operator, 5 and without departing from the spirit and scope of the invention as expressed in the claims.

The invention may be employed among other uses for the phototelegraphic transmission of pictures, manuscripts and for other visual or optical impressions, and for similar purposes, and it may also be applied to the reproduction of pictures by means of perforated recording strips or typed telegrams on either station, the impressions being transmitted in any suitable manner to the other station, and being utilized for re-constructing the original picture, a photographic recording device being influenced 20 by such perforated strips.

I claim:—

1. In the art of photoelectrically transmitting pictures and the like, changing the resistance of optically responsive electric conductors by irradiation, transmitting the changes of resistance produced to distant optically recording electric conductors, electrically connecting said optically responsive electric resistances with electric compensating resistances, adapted to compensate the lag of responsiveness in said optically sensitive resistances, and imparting additional constant preliminary irradiation to said compensating resistances.

2. In the art of photoelectrically transmitting pictorial and visual representations, changing the resistance of optically responsive electric conductors by irradiation, transmitting the changes of resistance produced to distant optically recording electric conductors, mounting optically responsive electric compensating resistances, adapted to compensate the lag of responsiveness in the electric conductors first mentioned in the relative vicinity thereof, and imparting a constant preliminary irradiation to said compensating resistances.

3. In the art of photoelectrically transmitting pictorial and visual representations, changing the resistance of optically responsive electric conductors by irradiation, transmitting the changes produced to distant optically recording electric conductors, mounting optically responsive electric compensating resistances, adapted to compensate the lag of responsiveness in the electric conductors first mentioned in series connection and in relative vicinity therewith, and imparting a preliminary irradiation to said compensating resistances.

4. In the art of photoelectrically transmitting pictorial and visual representations and the like, changing the resistance of optically responsive electric conductors by irradiation, mounting compensating addition-

al similarly optically responsive electric conductors in series and in relative vicinity of said first mentioned conductors, imparting a preliminary irradiation to said compensating conductors, closing an electric circuit 70 through said two kinds of conductors, arranging a variable bridge current in shunt on said circuit, and causing the variations produced in said bridge current to be transmitted to distant movable and optically recording electric conductors.

5. In the art of photoelectrically transmitting pictorial and visual representations and the like, changing the resistance of optically responsive electric conductors by 80 irradiations, compensating the lag of responsiveness of said conductors by mounting compensating additional similarly optically responsive electric conductors in series and in relative vicinity of said first mentioned conductors, imparting a constant preliminary irradiation to said compensating conductors, closing an electric circuit through said two kinds of conductors, arranging a variable bridge current in shunt 90 on said circuit, causing said current to pass through current reinforcing means, and transmitting the variations produced in said bridge current to distant optically recording electric conductors.

6. In the art of photoelectrically transmitting pictorial and visual representations and the like, changing the resistance of optically responsive electric conductors by irradiations, compensating the lag of responsiveness of said conductors by mounting compensating additional similarly optically responsive electric conductors of smaller sensitivity and greater coefficient of inertia than said first mentioned conductors in 105 series therewith and in the relative vicinity thereof, closing an electric circuit through said two kinds of conductors, imparting a preliminary irradiation to said compensating conductors, and transmitting the changes 110 and variations produced in said circuit to distant optically registering and optically influenced electric conductors.

7. In the art of photoelectrically transmitting pictorial and visual representations 115 and the like, changing the resistance of optically responsive electric conductors by irradiation, compensating the lag of responsiveness of said conductors by mounting compensating additional similarly optically responsive electric conductors of less sensitivity and greater coefficient of inertia than said first mentioned conductors in 120 series therewith and in the relative vicinity thereof, closing an electric circuit through said two kinds of conductors, imparting separate irradiation to the compensating conductors, arranging a variable bridge current in shunt on said circuit, causing said bridge current to pass through current rein- 130

forcing means, and transmitting the variations produced in said bridge current to distant optically recording electric conductors.

8. In the art of photoelectrically transmitting pictorial and visual representations and the like, changing the resistance of optically responsive electric conductors by irradiation, compensating the lag of responsiveness of said conductors by mounting 10 compensating additional similarly optically responsive electric conductors in series therewith and in the comparative vicinity thereof, closing an electric circuit through said two kinds of conductors varying the irradiation of said two kinds of conductors, and causing said variations to retardedly operate upon said compensating electric conductors, arranging a bridge current in shunt on said circuit, passing said bridge current 15 through current reinforcing means, and transmitting the changes produced in said bridge current to distant optically recording electric conductors, and optically influencing said conductors.

25 9. In the art of photoelectrically transmitting pictorial and visual representations and the like, changing the resistance of optically responsive electric conductors by irradiation, compensating the lag of responsiveness of said conductors by mounting 30 compensating electric similarly optically responsive conductors in series and in the comparative vicinity of said first mentioned conductors, projecting light from a common 35 source on said two kinds of conductors, and causing the compensating conductors to be retardedly irradiated by said light, closing an electric circuit through said two kinds of conductors, arranging a bridge current 40 on said circuit, passing said bridge current through current reinforcing means, and transmitting the changes produced in said bridge current to distant optically sensitive recording irradiated electric conductors.

45 10. Device for photoelectrically transmitting pictorial, visual or other representations, comprising a sending and transmitting station, and a receiving station, electric conducting means of optically controlled varying resistance at the sending station, and optically controlled varying compensating electric resistance means in series with the other electric optically controlled conductors at said transmitting station, and means to 50 impart a constant retardation of irradiation at the transmitting station to one of the electric optically responsive conducting means, and irradiating means at both stations and current increasing valves intermediate the 55 transmitting and receiving stations.

60 11. Device for photoelectrically transmitting pictorial, visual and other representations, comprising a sending or transmitting station, and a receiving station, electric conducting means with optically controlled va-

rying resistance at the sending station, compensating, similarly optically responsive electric conducting means at the said sending station and in series with the other optically responsive conductors at said station, 70 means adapted to produce a constant preliminary irradiation of said compensating conducting means, movable current-change-responsive and indicating means, shunted on the conducting means of said sending or 75 transmitting station, and adapted to transmit the change of resistance to the receiving station, and irradiating means at both stations.

12. Device for photoelectrically transmitting pictorial, visual and other representations, comprising a sending station and a receiving station, and conducting circuits for both stations, electric conducting means with optically controlled varying resistance 80 at the sending station, compensating, similarly optically responsive electric conducting means at the sending station in series with the other optically controlled resistance, a variable-resistance bridge circuit shunted 85 on the conducting circuit of the sending station, light-projecting means at both stations, a galvanometer at the sending station, inserted on said bridge circuit, and intermediate the light-projecting means and 90 the optically responsive conducting means, reproducing means at the receiving station, and a message-receiving galvanometer in the conducting circuit of the receiving station and intermediate the light-projecting 95 means and the reproducing means, and current-reinforcing tubes on the galvanometer-circuit.

13. Device for photoelectrically transmitting pictorial, visual and other representations, comprising a sending station and a receiving station, an electric circuit at each of said stations and optically influenced reproducing means at the receiving station, an optically controlled electric conductor 105 with varying resistance at the sending station included in the electric circuit thereof, a source of light at each station and a displaceable picture carrier intermediate said conductor and said source of light at the 110 sending station, a compensating, similarly optically responsive conductor with varying resistance at the sending station, adapted to be influenced by the source of light and in series with the first-mentioned conductor 115 of said station, a galvanometer at the sending station intermediate the source of light and the compensating conductor, a bridge circuit, including said galvanometer and shunted off from the conductor circuit, a similar recording galvanometer at the receiving station, electrically influenced by the first-mentioned galvanometer and intermediate 120 the source of light and the reproducing means at said receiving station, current- 125 130

reinforcing means on the galvanometer-circuit, and an oscillatable foil on each galvanometer opposite the source of light, and a variable regulating resistance in the sending galvanometer circuit.

14. Device for photoelectrically transmitting pictorial, visual and other representations, comprising a sending station and a receiving station and electric circuits at said stations, electric conducting means with optically controlled varying resistance on the circuit of the sending station, a source of light at each station opposite said electric circuits and in line with the optically controlled resistance of the sending station, picture-carriers in line with the sources of light and in line with the optically controlled conductor at the sending station, a similarly optically influenceable compensating conductor at the sending station in series with the first-mentioned conductor and in the comparative vicinity thereof and opposite the source of light, means associated with the picture carrier of the sending station for retarding the irradiation of said compensating conductor, current-reinforcing means at said sending station, and movable current-change responding means shunted on said reinforcing means and intermediate the source of light and the compensating means, and electrically influenced movable recording means at the receiving station intermediate the source of light and the picture-carrier thereof.

15. Device for photoelectrically transmitting pictorial, visual and other representations, comprising a sending station and a receiving station, a source of light at each station, a movable picture-carrier at each station opposite the source of light, electric conducting means with optically controlled varying resistance at the sending station in line with the picture carrier and adapted to be influenced by the source of light, a similar optically influenceable compensating conductor at the sending station in series with the first-mentioned conductor and opposite the source of light, means on said picture carrier for retarding and controlling the irradiation of said compensating conductor, current-reinforcing means at said sending station, and movable, electrically influenced, light-controlling means shunted on said reinforcing means and intermediate the source of light and the compensating means, electrically influenced similar light controlling and recording means at the receiving station intermediate the source of light and the picture carrier thereof, and adapted to be influenced by the light-controlling means at the sending station.

16. Device for photoelectrically transmitting pictorial, visual and other representa-

tions, comprising a sending station and a receiving station, a source of light at each station, a movable translucent picture carrier at each station opposite the said source of light thereof, electric conducting means with optically controlled varying resistance at the sending station associated with the picture-carrier and adapted to be influenced by the source of light, a similar optically influenceable compensating conductor at the sending station in series with the first mentioned conductor and relatively adjacent thereto and opposite the source of light, a shutter at the sending station intermediate the source of light and the picture-carrier thereof, transversely slotted and codirectionally movable with relation to the picture-carrier and intersecting the path of light, current-reinforcing means on said sending station, and movable light-controlling means shunted on said reinforcing means and intermediate the source of light and the compensating conductor, electrically influenced similar light-controlling and recording means at the receiving station intermediate the source of light and the picture carrier thereof, and adapted to be influenced by the light-controlling means at the sending station.

17. In the photoelectric transmission of pictorial, visual and other representations, a sending station and a receiving station, electric conducting means with optically sensitive and responsive serially connected resistances at the sending station, a movable picture carrier at each station, irradiating means on each station, telegraphic transmitting means at the sending station electrically influenced by the optically responsive resistances, and similar telegraphic means at the receiving station adapted to be influenced by the transmitting means at the sending station and current reinforcing means intermediate the stations.

18. In a photoelectric transmission of pictorial, visual and other representations, two distant stations, optically sensitive and responsive, serially connected electric resistances at one of said stations, a picture carrier at said station, and light irradiating means in line with said picture carrier and said optically responsive resistances, movable, light-controlling means electrically connected to said optically responsive resistances, corresponding recording means at the other station and adapted to be influenced by the first mentioned movable light-controlling means, a picture carrier at the last mentioned station in line with the recording means of said station, and means to impart additional irradiation to one of the said optically responsive resistances.

ARTHUR KORN.
